UNITED STATES PATENT OFFICE.

WILLIAM H. MEAD, OF AUTAUGAVILLE, ALABAMA.

WIRES TIGHTENER AND TWISTER.

1,418,956.

Specification of Letters Patent. Patented June 6, 1922.

Application filed November 12, 1921. Serial No. 514,790.

To all whom it may concern:

Be it known that I, WILLIAM H. MEAD, a citizen of the United States, residing at Autaugaville, in the county of Autauga and

5 State of Alabama, have invented new and useful Improvements in Wire Tighteners and Twisters, of which the following is a specification.

This invention relates to improvements 10 in wire twisting devices and more particularly to a twisting device adapted to twist loops in the wire of a wire fence, so that the strands of the fence will be tensioned to take up slack and the like.

15 Another object of the invention is to furnish a device of the above character which is simple and inexpensive in construction and which will efficiently operate under all conditions.

20 Another object of the invention is to provide a wire twisting device including a co-operating loop and hook, and means for holding the hook in a fixed position so that the device may be readily twisted to facilitate placing a twist or loop in the wire operated upon.

With the foregoing objects outlined and with other objects in view which will appear as the description proceeds, the invention 30 consists in the novel features hereinafter described in detail, illustrated in the accompanying drawing and more particularly pointed out in the appended claims.

Referring to the drawing:

35 Figure 1 is a perspective view of the improved device and showing the same secured to a wire fence strand.

Fig. 2 is a side view of the same showing in dotted lines the position of the hook lever 40 before the same has pressed a portion of the wire strand into the loop of the device.

Fig. 3 is a view similar to Fig. 2 but showing the device turned from a horizontal to a vertical position so that it may be swung 45 about an axis passing through its loop portion to twist the wire which is grasped by the hook and looped portion.

Fig. 4 is a top plan of the device.

Fig. 5 is a perspective view of a type of 50 loop formed by the improved tool.

In the drawing 1 designates a rod or shaft provided at one end with an angular crank portion 2. The other end of said rod or shaft is bent to form a loop 3, the short arm 55 4 of which is secured to the member 1 by means of a pivot pin 5.

Mounted on the pin 5 is a lever 6 provided at one end with a hook 7 and adapted at its other end to be secured in locked position by a catch or hook 8. The member 6 is preferably formed of resilient or flexible material so that the outer end portion 9 of the lever may be swung in a clockwise direction relatively to the rod 1 to permit the outer end portion of said lever to be passed beneath the 65 catch or hook 8.

In operation the loop 3 is placed upon the strand 10 of a wire in a fence and at this time the lever 6 and hook 7 are swung in an anticlockwise direction sufficiently to permit 70 the strand 10 to be passed between the lower face of the loop 3 and the upper face of the hook 7. Then the outer end 9 of the lever 6 is swung in a clockwise direction to cause a kink to be formed in the portion of the 75 strand 10 which lies between the opposite sides of the loop 3. The lever 6 is swung downwardly or in a clockwise direction until it passes over the catch or hook 8, and then the end portion 9 is moved inwardly 80 toward the rod 1 so that said end portion may be passed upwardly under the hook 8. When the device is in this position the parts are swung from the horizontal position which they occupy in Fig. 2 to the vertical 85 position shown in Figs. 3 and 4. Then the handle or crank 2 is grasped by the operator and the device is turned in a vertical plane in the direction of the arrow shown in Fig. 4, about an axis passing through the loop, and 90 this causes the kinked portion of the wire to be formed into a loop 11 such as shown in Figure 5.

From the foregoing I believe that the construction, operation and advantages of the 95 present invention may be readily understood by those skilled in the art and I am aware that various changes may be made in the construction illustrated without departing from the spirit of the invention as expressed in 100 the following claims.

Without limiting myself to details, I will state that the parts 1, 3 and 4 may be, and are preferably made in one piece, and can be, if desired made of wrought iron or steel. 105 Cast steel or cast iron can also be used in some cases, for cheapness, if desired. The rod 1 (from the pivot 5 to the handle 2) may be 17 inches long, and may be round stock about $\frac{1}{2}$ inch diameter. The crank handle 2 110 may be 6 or 7 inches long. The loop 3 may be $1\frac{1}{2}$ in diameter. The hook lever may be

20 inches long (from 7 to 9) and may be $\frac{3}{4}$ inch wide and $\frac{1}{4}$ inch thick, and made preferably of steel.

What is claimed and desired to be secured 5 by Letters-Patent is:

1. A wire twisting device including a rod having a crank at one end and a loop at its other end, a lever pivotally connected to said rod and provided at one end with a hook which cooperates with said loop to engage a wire, and means for locking said lever in a fixed position relatively to said shaft.
2. A wire twisting device including a rod having one of its ends bent to provide an angular extending crank, a loop formed at the opposite end of said rod and integral therewith, a lever pivotally connected to said rod and having a hook at one end cooperating with said loop to grasp a wire, and means 15 for locking said lever in a fixed position on said rod.
3. A wire twisting device including a rod having one of its ends bent to provide a loop

terminating in a short arm, a pin connecting said short arm to said rod, a crank integral 25 with the other end of said rod and extending in a direction substantially parallel to the axis of said loop, a lever pivotally mounted on said pin and provided with a hook co-operating with said loop to grasp a wire, 30 and means for securing said lever in a fixed position on said rod.

4. A wire twisting device including a rod having one of its ends bent to provide a loop terminating in a short arm, a pin connecting said short arm to said rod, a lever pivotally mounted on said pin and having a hook at one end cooperating with said loop to grasp a wire, a crank carried by said rod, 35 and a second hook mounted on said rod and engageable with said lever for holding the same in a fixed position.

In testimony whereof I affix my signature.

WILLIAM H. MEAD.
